UNITED STATES PATENT OFFICE.

JOHN W. HEIDER, OF CHICAGO, ILLINOIS, ASSIGNOR TO THÉODORE F. LAWRENCE, OF SAME PLACE.

BRONZING-MACHINE.

SPECIFICATION forming part of Letters Patent No. 258,201, dated May 16, 1882.

Application filed March 7, 1882. (No model.)

To all whom it may concern:

Be it known that I, JOHN W. HEIDER, residing at Chicago, in the county of Cook and State of Illinois, and a citizen of the United States, have invented new and useful Improvements in Bronzing-Machines, of which the following is a full description, reference being had to the accompanying drawings, in which—

Figure 1 is a plan. Fig. 2 is a side elevation. In Figs. 1 and 2 the cylinder and other parts shown are in the position which they occupy when a sheet which has been bronzed is just ready to pass from the bronzing-cylinder to the delivery apparatus. Fig. 3 is a front elevation, the front of the bronze-fountain and of the bronzing-chamber being removed. Fig. 4 is a vertical section at line *x* *x* of Fig. 1, the bronzing-cylinder and the delivery-cylinder being in the position which they occupy just before the grippers of the bronzing-cylinder grasp the sheet. Figs. 5 and 6 are details, Fig. 6 being a section of the parts shown, taken at line *y*, Fig. 5.

One object of my invention is to provide for agitating the bronze automatically; and my improvements which relate to this feature consist in providing the bronze-fountain with an agitator which is automatically reciprocated in a longitudinal direction with respect to the fountain, in connecting such agitator with the bronzing-pad by means of a cross-bar, so that the two will move simultaneously, in a cam combined with the agitator-shaft and bronzing-pad shaft, and lever-connections for operating such shafts.

My invention further consists in arranging the head upon the nipper-shaft which carries the sheet into the machine upon the inside of the bronzing-cylinder, and providing such head with two slots in the periphery of the head, so formed and arranged that the nippers will act quickly when grasping the sheet to carry it into the machine, but will operate more slowly when releasing the sheet.

In the drawings, A represents a main frame which supports the bronzing machinery, as usual, the bronzing-chamber being inclosed as nearly as possible, as is common, to prevent the escape of the bronze which does not

B is an inclined table, on which the sheets to be bronzed are placed, and from which they are fed to the machine.

C is the cylinder upon which the sheets are held while being bronzed.

D is the bronze-fountain, having a narrow longitudinal opening in the bottom, through which the bronze falls upon the sheet, which opening can be enlarged or diminished in width by means of a sliding plate, as usual. I also provide slides, by the use of which any desired portion of this opening may be entirely closed, as may be desired in bronzing sheets of different widths.

E is a longitudinal shaft, having bearings in the ends of the bronze-fountain D, and located preferably above the opening in the bottom thereof, and it is provided with a number of thin teeth, *g*, or short arms, which extend downward into the opening in the bottom of the fountain. The shaft E is so secured in the fountain that it can have a reciprocating longitudinal movement without rotating, and such shaft and the teeth thereon together form an agitator. The shaft E extends some distance beyond the fountain at one end, and is there provided with a coil-spring, *a*, which is so arranged that its tendency is to hold and throw such shaft outward.

F is a shaft or bar which carries a bronzing-pad, which pad is arranged and operates substantially in the usual manner, except as herein specified. This shaft or bar F extends out beyond the frame of the machine upon one side, as shown in Fig. 1, and it is provided with the coil-spring *b*, which is so arranged that its tendency is to throw the shaft F outward.

The outer ends of the shafts E and F are connected together by means of a short cross-bar, *c*, so that the two shafts E and F vibrate together. *d* is the bronzing-pad.

G are cleaning-rollers, arranged and operated as usual.

e are thin bars let into the table B, as usual. *f* are guides, the lower ends of which rest upon the bars *e* until the sheet is ready to be grasped by the grippers, when such guides are raised in the usual manner.

H is a shaft which carries the grippers of the bronzing-cylinder. It is supported in suit-

able bearings, as usual, one of which, I, is shown in Fig. 5, upon one side of which are secured two stops, *h*.

J is a head upon one end of the shaft H, which head is located within the cylinder C, which enables me to bring the casing upon that side of the machine close to the end of the cylinder C. In the periphery of the head J there are two recesses or open slots, *i* and *j*, which are different in form, as shown in Fig. 4. By means of these slots and pins *k* and *k'*, secured upon the inside of the frame, a partial rotation is given to the head J, the pin *k* being arranged to engage with the slot *i*, and the pin *k'* being arranged to engage with the slot *j*. The slot *j* is considerably wider at its outer end than is the outer end of the slot *i*. Upon the inside of the head J is a pin, *l*, located between and arranged to come in contact with the stops *h*. *m* is a rod, one end of which is pivoted upon the inside of the head J. The other end passes through a hole in a plate or bar, *n*, upon the inside of the cylinder C.

o is a coil-spring around the rod *m*, between a collar thereon and the bar *n*.

p is one of the grippers on the shaft H, which grippers are arranged to open and close, as usual, except as herein specified.

K is the delivery-cylinder, provided with a shaft carrying grippers, constructed and operating as usual.

I have shown by dotted lines in Fig. 4 the position of the pins *k* *k'*, which cause the head J to move, and also the position of the pins which operate the head of the gripper-shaft of the delivery-cylinder.

The guides *f* are secured at one end to a rock-shaft, as usual, and motion is given to this shaft by means of the arms *q* *q'*, which are operated by means of an eccentric on the shaft of the cylinder C.

The devices which give a vibratory movement to the agitator and to the bronzing-pad are as follows:

L is a disk upon the shaft of the cylinder C, provided upon one side with a series of cams, *r*.

M is a bell-crank lever, pivoted at or near its center to an arm, *N*, which projects out from the side of the frame. The lower end of this bell-crank lever is provided with a friction-roller arranged to come in contact with the face of the bar *e*, which connects the shafts of the agitator and bronzing-pad.

P is a bar, the upper end of which is pivoted to the upper and inner end of the bell-crank lever *M*. The other end of this bar *P* is provided with a friction-roller, arranged to come in contact with the periphery of the cam-disk *L*.

Q is a bar, the upper end of which is pivoted to the bar *P*, and the lower end is pivoted upon a projection upon the side of the main frame. The bar *Q* serves the purpose of steady-ing the bar *P* and keeping its lower end in proper position.

R are devices for adjusting the position of the cleaning-rollers *G*.

The slot *j* in the head J is not cut in a direct line from the periphery toward the center of the head, but is at a considerable angle thereto. This location of the slot is important in causing the grippers to release the sheet gradually.

The operation is as follows: The sheets to which bronze is to be applied are fed to and delivered from the machine substantially in the usual manner, there being these differences between the devices commonly used and those I have shown and described: The head J is located inside the cylinder instead of outside thereof, which enables me to place the frame upon this side very close to the edge of the cylinder C. The form of the slot *i* in the head J is such that when this slot comes in contact with the pin *k* the nippers will close upon the sheet very rapidly; and the form of the slot *j*, the same being much larger than *i*, is such that when this slot *j* comes in contact with the pin *k'* the nippers will be opened gradually for the purpose of giving the nippers upon the delivery-cylinder K more time to grasp the sheet. The head J, which is upon the gripper-shaft of the delivery-cylinder K, is located within the cylinder K. The rod *m* and coil-spring *o* serve the purpose of holding the head J, in whatever position it may be placed, until forcibly changed by coming in contact with the pins *k* *k'*.

The agitator in the bronze-fountain and the bronzing-pad are caused to vibrate longitudinally and simultaneously, and at the proper time for delivering and distributing the bronze to and upon the sheet, by means of the cam-disk *L*, bar *P*, and bell-crank lever *M*, and springs *a* *b*. The tendency of the springs *a* and *b* is to throw and hold the two shafts *E* and *F* out, and these shafts are caused to vibrate longitudinally and rapidly by the action of the springs *a* *b*, and the movement of the bell-crank lever, which is operated by the cams *r*, which act upon the lower end of the bar *P* as the cylinder C revolves. The lower end of the bell-crank lever forces the shafts *E* and *F* inward. The springs *a* and *b* throw them outward.

The springs *a* and *b* are not a necessity, and motion could be given to the agitator and bronzing-pads in both directions without these springs; but this would require additional mechanism.

The agitation of the bronze in the fountain by hand is not reliable, and does not deliver the bronze uniformly; but my agitator is uniform and certain in operation. The simultaneous movement of the agitator and the bronzing-pad is a desirable feature.

What I claim as new, and desire to secure by Letters Patent, is as follows:

1. In a bronzing-machine having a bronze-fountain provided with a longitudinal slot in its bottom, a longitudinal reciprocating agitator located in said fountain, and composed of a shaft and depending fingers, the latter

being adapted to move in the slotted bottom of the fountain, substantially as and for the purpose described.

2. In a bronzing machine, the combination 5 of an agitator arranged in the bronze-fountain to reciprocate in a longitudinal direction with respect thereto, the bronze-pad, and the cross-bar connecting the latter with the agitator, and serving to simultaneously operate 10 both the agitator and the pad, substantially as and for the purpose described.

3. In a bronzing-machine, an agitator located in the bronze-fountain and a bronzing-pad connected with the agitator, in combination with

a disk, L, provided with cams *r*, bell-crank lever M, and bar P, substantially as and for the purpose specified. 15

4. The head J of the gripper-shaft of the cylinder C, provided with the slots *i* and *j*, formed as shown and described, in combination with the pins *k* and *k'* upon the frame, whereby the grippers will act quickly when grasping the sheet and will open slowly when releasing the sheet, substantially as specified. 20

JOHN W. HEIDER.
